UNITED STATES PATENT OFFICE.

GEORGE R. MURRAY, OF CLEVELAND, OHIO.

STONE GRINDING AND POLISHING MACHINE.

1,230,759.

Specification of Letters Patent. Patented June 19, 1917.

Application filed March 1, 1915. Serial No. 11,142.

To all whom it may concern:

Be it known that GEORGE R. MURRAY, a citizen of the United States, residing at Cleveland, in the county of Cuyahoga and State of Ohio, has invented certain new and useful Improvements in Stone Grinding and Polishing Machines, of which the following is a specification.

This invention pertains to a stone grinding and polishing machine, and the invention consists in an improvement in or upon the machine shown in my application for Letters Patent of the United States, filed August 3, 1912, Ser. No. 713,218.

In the accompanying drawings, Figure 1 is a plan view of the machine with the table partly broken away at the bottom to show the endless track beneath. Fig. 2 is a cross section, enlarged, on a line substantially central of Fig. 1, right to left. Fig. 3 is a sectional view on line 3—3, Fig. 2 and Fig. 4 is a sectional elevation corresponding in part to Fig. 3 but on the axis of one of the grinders and showing the grinder and its shaft and water supply connection and associated parts. Fig. 5 is a plan view of one of the grinders as seen in Fig. 4 with wedges to secure the grinding members, and Fig. 6 is a plan view of a grinder showing 25 clamps to secure the said members, and Fig. 7 is a side elevation of the machine. Fig. 8 is a clamp detail.

All the foregoing views are necessarily on a greatly reduced scale as the machine is of very large proportions, say 25 to 50 feet across the stone carrying table, T, and some of the stones S thereon may be six to eight feet in length and the elevations of some of the parts correspond to these proportions, the rule of proportions being observed as nearly as possible.

The stone carrying table T is of ring shape rather than a disk and adapted to be rotated on a circular track 2 beneath, having wheels or rollers for this purpose. A ring gear 3 is provided at the inner edge of the table which is engaged by power or driving means through the shaft s and gear 4. A comparatively slow movement or rotation of the said table is found sufficient and this movement is operatively associated with a reciprocating action of the grinders G across the face of the stones S on the exposed portion of the table. It will be seen that the stones are placed flatwise upon the table in position to be carried around suc-

cessively beneath the grinders and to be subjected to the grinding action in proportion to their own rate of travel and the speed of the grinders, so that they may pass beneath the grinders one or more times as shall be deemed desirable. Usually a single passage is sufficient.

In work of this kind it is of the first importance that the exposed surface of the stone should be kept thoroughly moistened throughout the grinding operation, and to this end I provide the table T with flanges or rims 7 at its edges of at least such depth as will submerge the stone. Rim 7 may be made high enough or is supplemented by a ring or band r to provide an effective guard for flying pieces of stone and flying spray. The water is supplied to the table through the tubular shafts 5 of the respective grinders by pipe 6 and flexible hose connection h to accommodate the travel. A rigid traveling frame F has lateral projections f at its side edges which in a sense serve as bearings for said shafts 5, and the said shafts and grinders are vertically adjustable in said bearings or guides within limits by means of an adjusting screw 8 and an arm 9 threaded for the passage of said shaft and having a guide head 9' slidable on frame F. The said screw is mounted at its ends in frame F and rotated by means of bevel pinion 10 thereon and a hand rotated gear 12 in mesh therewith, or the equivalent.

Both grinders G are supported and operated in like manner, and the frame F carrying said grinders and their associated parts is slidably mounted in its four angles or corners on guides or guide rods R mounted at their ends in or upon the base frame B. The said frame F and the grinders and all the parts operatively pertaining thereto are adapted to reciprocate on said rod R while the said grinders are axially rotated at the same time and the table T is carried around beneath the same, thus making a triple moving operation. Reciprocation is effected by means of a suitable power medium or engine E and connecting rod or shaft 15 therewith and with the center of frame F, and rotation of said grinders is through the sheaves 16, 17 and 18 and the cable 22 running thereon. Thus, the sheave 16 is slidably splined on the upper end of shaft 5 and has its bearing on the projection f at that corner of frame F and the sheave 17 is mounted on a traveler 19 hav-

ing rollers or wheels 20 running on fixed tracks or rails 21. The cable or belt 22 runs over these several sheaves or wheels and over idler 23 above, and power is applied to this line of mechanism to rotate the grinders by means of the shaft 25 which carries sheave 18 and by belt 26, or equivalent driving connections, to a pulley 27 on said shaft. The cable 22 is drawn taut over its several carrying sheaves and the traveler 19 is held in counterbalanced working relations by the respective counterweights 28 and 29, and the cords 30 and 31 connect with said traveler and said weights, respectively. Such play as the wheel 17 may need in respect to the grinders in their reciprocating travel is provided for in the said counterweights and cords.

Reciprocation of the grinders across the face of the stones is therefore by the power medium E, while rotation thereof is through the cable or belt 22 from the power driven shaft 25 and wheel 18 thereon. Each grinder has its own driving mechanism, and one or both can be used at the same time and both may be alike or one to do the rough work and the other the polishing, thus completing the work in a single treatment of the stones.

The said shafts 5 are rotatable and free to slide in the projections f, Fig. 4, and each shaft has collars 30' and 31' clamped thereon above and below the arm 9 respectively. Another collar 32, is sleeved on shaft 5 next beneath collar 31' and carries ball bearings 33 for the collar 31'. A counterbalancing lever 34 has a yoke 35 at its inner end engaged by screws 36, and said collar 32 is held in permanently raised position as against collar 31' by the weight 37 on said lever 34. An arm 38 from the part 9 serves as a pivot support for the lever 34.

In operation the collar 30' serves to limit the depth of cut of the grinder upon the stone as it comes down into a position of rest on the stop member 9, and the collar 31' fixes the limit to which the grinder can be raised by impinging against the stop 9 when the grinder and its shaft is raised by the lever 34 and its counterweight 37. This weight and lever serve also to graduate the down pressure under which a grinder does its work, and the grinder can be more or less raised thereby or lifted completely above the stone, as seen in Figs. 3 and 4.

One method of securing the grinding or abrading members or block g is illustrated in Figs. 4 and 5 wherein wedges w and plaster of Paris are employed and whereby the said member can be lowered as it becomes worn. Another method is illustrated in Fig. 6, wherein clamps 42 take the place of the wedges and the grinder has openings larger than the abrading blocks and a flange 41 is provided at one side of each opening

and a clamping member 42 at the other side set partially into said opening and engaged by bolts with the flange. In this way, the grinding blocks g in the abrading or grinding members are adapted to be fixed to dip more or less into the water within the trough carrier or table for the stone and to be adjusted downward as they wear away. Several adjustable overflow pipes 44 are provided for the rotatable carrier T to maintain a body of water within the ring trough thereof at any desired working level, and the stones or slabs are submerged more or less as the requirements demand. The water is fed centrally to the grinders through the hollow shaft 5 and forcibly ejected from beneath the grinding wheel by the relatively rapid rotation of the wheel and the outflow is from the center of the wheel through the radial spaces between the grinding blocks, thereby keeping a flowing body of fresh water constantly in the circular path of each grinding block and in this way overcoming heating or fluxing or injury to the surface of the stone and making a fine and smooth grinding operation possible with a minimum of wear on the grinding blocks. A single grinding wheel may be used, but two grinding wheels G are preferable as one may be used in advance of the other for rough grinding and the follower wheel for finer finishing results. Each wheel G has a vertically adjustable rim guard 45 which does not prevent the radial outflow of the water but does prevent broken pieces of stone or the grinding blocks from flying outward to the possible injury of the observer and operator. A counterweight 49 is connected to the slidale reciprocating frame F by a cable 50, see Fig. 2, to cause a return movement of the frame after each forward movement imparted thereto by engine E, the advantage of this arrangement being that the reverse movements of the frame and the grinders when at work, are effected uniformly and steadily with a minimum of vibration and jerk.

What I claim is:

1. In a stone grinding machine, a substantially ring-shaped rotatable carrier for a slab to be ground, a grinding wheel and a reciprocable support therefor adapted to traverse said table, means to rotate and means to raise and lower said wheel upon said support, and means to deliver water centrally through and beneath said wheel during rotative and reciprocable movements thereof.

2. In a stone grinding machine, a table for the stones, a supporting frame and a rotatable grinding member having a shaft vertically slidale therein, a counterweighted lever engaged with said shaft, collars on said shaft, and a vertically-movable engaging part for said collars having a screw to

adjustably fix it at different elevations to limit the vertical movement of the grinding member in both directions relatively to the stones on the said table.

5 3. In a stone grinding machine, a frame having cross rods and a slidable mounting thereon, rotatable grinding wheels horizontally disposed beneath said mounting at opposite sides thereof and provided with vertical shafts rotatably and slidably carried by said mounting, means to adjustably fix the slidable limits of said shafts, means to adjustably counterbalance the grinding wheels, and separate power-applying members carried by said mounting and slidably splined to said shafts.

4. In a stone grinding machine, a rotatable table to carry the stones, a reciprocable frame slidably mounted over said table and 20 a horizontally rotatable grinding member mounted thereon, in combination with actuating means for said table, frame and member respectively, and a counterweight connected with the said frame to promote 25 uniform and steady reversal movements of the said frame and grinding member during grinding operations.

5. In a stone grinding machine, a grinding member mounted to rotate horizontally, 30 and means to simultaneously reciprocate and rotate said member, a rigid frame carrying said member and horizontally disposed rods on which said frame is slidably mounted, in combination with a ring-shaped carrier 35 adapted to rotate the stones transversely beneath and in contact with the said grinding member.

6. A stone grinding machine, comprising a rotatable grinding member and means to 40 reciprocate said member while under rotation, in combination with a rotatable ring-shaped carrier for the stones provided with adjustable border flanges adapted to vary the depth of water to submerge the stones in 45 the grinding operation.

7. In a stone grinding machine, a rotatable grinding member having a series of grinding blocks fixed therein and a water inlet at its middle relatively above the working surface of said blocks and an outlet for the 50 water radially from said inlet between said blocks, and means to rotate and reciprocate the said member at the same time.

8. In a stone grinding machine, a horizontally reciprocating frame and a grinding 55 wheel rotatably mounted thereon having grinding blocks fixed therein; in combination with a rotatable stone carrier having a fixed axis of rotation and adapted to be traversed by said grinding wheel in rotat- 60 ing and reciprocating movements.

9. In a stone grinding machine as described, a slidable frame and means to reciprocate the same horizontally, a grinding member and a shaft therefor rotatably and 65 slidably mounted in said frame, in combination with means to raise and lower said member comprising a separate adjusting screw supported in said frame, an arm slideable on said frame and actuated by said screw and means on said shaft above and below said arm adapted to be engaged thereby and to limit the movements of said shaft vertically.

10. A stone grinding machine, comprising 75 a ring-shaped table adapted to be rotated about a fixed axis, in combination with a grinding member and means to rotate and reciprocate said member at the same time, said means comprising a reciprocating 80 frame having fixed supports and means to fix the working position of said grinding member in respect to said table.

In testimony whereof I affix my signature in presence of two witnesses.

GEORGE R. MURRAY.
